UNITED STATES PATENT OFFICE.

EUGENE DE KLEIST, OF NORTH TONAWANDA, NEW YORK.

PNEUMATIC MOTOR.

No. 807,288.

Specification of Letters Patent.

Patented Dec. 12, 1905.

Application filed December 21, 1903. Serial No. 185,965.

To all whom it may concern:

Be it known that I, EUGENE DE KLEIST, a citizen of the United States, residing at North Tonawanda, in the county of Niagara and State 5 of New York, have invented new and useful Improvements in Pneumatic Motors, of which the following is a specification.

This invention relates more particularly to the pneumatic motors employed for propelling 10 the perforated music-sheets of piano-players and automatic musical instruments, although the same is also useful for operating other devices. The invention has special reference to motors of this class which comprise a shaft 15 having three or more cranks located progressively around the same, a number of bellows each having its movable board connected with one of said cranks, and valves for controlling the exhaustion of the air from the bellows and 20 the admission of the air thereto in such a manner that the bellows are collapsed successively and caused to impart a continuous rotary motion to the shaft.

One of the objects of my invention is to improve 25 the construction of the valve mechanism with a view of rendering the motor compact and insuring a tight joint between the suction-valves and their seats.

Another object is the provision of simple 30 and convenient means for adjusting the valves, so as to keep the cranks of the motor-shaft off the dead-center.

In the accompanying drawings, Figure 1 is a front elevation of the motor with the front 35 plate of the suction-valve chambers removed. Fig. 2 is a transverse vertical section in line 2 2, Fig. 1, with said front plate in place. Fig. 3 is a similar section taken in a different plane and showing the valves in a different position 40 from that illustrated in Fig. 2. Fig. 4 is a horizontal section in line 4 4, Fig. 1.

Similar letters of reference indicate corresponding parts throughout the several views.

A indicates the casing or wind-board of the 45 motor, and B the crank-shaft, which is journaled in standards C, mounted on the casing and from which motion may be transmitted to the part to be driven by any suitable means. When the motor is used for propelling a perforated music-sheet, one of the winding-rollers of the sheet is connected with the motor-shaft by gearing or an endless chain in a well-known manner.

D indicates the bellows or motor-pneumatics 50 secured in an upright position to the back of the wind-board and having their movable

boards connected with the cranks of the shaft by rods or pitmen e in the usual manner. Each bellows communicates, by means of a passage f, with an upright air channel or duct 60 f', arranged in the upper portion of the wind-board, as seen in Figs. 2 and 3, these channels being arranged opposite the several bellows, respectively, as shown by dotted lines in Fig. 1. Each of these channels communicates with the atmosphere by an inlet-port g, formed in the front wall of the wind-board. To the outer sides of these inlet-ports sliding inlet-valves g' are applied which are guided in suitable ways g² and connected by rods g³ 70 with lugs g⁴ at the inner ends of the corresponding pitmen e, so that said valves are opened and closed by the rising and falling movements of said pitmen.

H indicates upright suction-chambers arranged in the lower front portion of the wind-board A and closed on all sides. Each of these chambers is connected with the lower end of the adjacent air-channel f' by a port i, and with a horizontal suction-channel J by a port j. 75 This suction-channel is separated from the upright air-channels f' by a partition J', and communicates with an air-trunk k, connected with a suction pump or bellows, (not shown in the drawings,) which exhausts the air from 80 said suction-channel. Each of the suction-chambers H contains a sliding suction-valve l, arranged to open or close the lower suction-port j. These suction-valves are guided in suitable ways l', secured to the front wall of 85 the wind-board, and each of the same is connected with the companion inlet-valve g' by a rod m passing through an opening in the top of the corresponding valve-chamber H. The inlet and suction valves of each pair are connected in such a manner that when the suction-valve is closed the inlet-valve is opened, and vice versa. In order to permit the valves of each pair to be adjusted toward and from 90 each other, the lower end of each connecting-rod m is provided with an eye or opening m', which engages over a pin n, carried by the suction-valve, while the upper end of the rod is screw-threaded and engages in a threaded opening formed in a lug o, projecting from 95 the inlet-valve g'. In adjusting the valves the eye of the rod is sprung out of engagement with the pin n, the rod is screwed up or down in the lug o, and the eye of the rod is then again sprung over the pin. 100

Each of the connecting-rods g³ is preferably composed of adjustable sections connected at 110

their opposing ends by a longitudinal screw *p*, as shown, so that upon removing the pivot-pin at one end of the rod its released section can be turned on the other section for shortening or lengthening the rod, after which said pivot is replaced.

In the operation of the motor when the inlet-valve *g* of a pair is closed and the suction-valve *l* is open, as shown in Fig. 3, the air is exhausted from the companion bellows through the passage *f*, upright channel *f'*, suction-ports *i,j*, and horizontal suction-channel *J*, thereby collapsing said bellows and causing the same to turn the motor-shaft about a third of a revolution. When the position of the valves is reversed by the rotation of the shaft, as shown in Fig. 2, the bellows is cut off from the suction-channel *J* and the atmosphere is allowed to enter the bellows through the open inlet-port *g*, the channel *f'*, and passage *f*, thereby expanding the bellows and returning its movable board to its former position. In this manner the three bellows act successively upon the cranks of the motor-shaft, rotating the shaft continuously in a manner common to motors of this kind.

The upper ports *i* of the valve-chambers *H* are preferably so large that they are not fully covered by the suction-valves *l* in the uppermost position of the latter, as shown in Fig. 2. By this construction when any one of the inlet-valves is open a portion of the atmosphere entering the corresponding chamber *f'* also enters the companion valve-chamber *H* through the constantly-open port *i* and exerts its pressure against the back of the corresponding suction-valve, thereby forcing said valve firmly against its seat and reducing leakage of air past the same to a minimum. By providing an adjustable connection between each pair of valves and the corresponding crank of the shaft *B* the movement of the valves relative to the ports can be properly regulated and any inaccuracies in the position of the cranks can be compensated for, and by providing a similar connection between the companion valves of each pair one valve can be given the proper lead with reference to the other to insure a continuous rotation of the shaft and prevent the cranks from getting on the dead-center.

The arrangement of the suction and air channels *J f'* one directly below the other and the corresponding arrangement of the sliding suction and air-inlet valves affords the advantage of materially reducing the depth or width of the motor from front to rear, this being desirable when the motor is used in connection with automatic piano-players, in which compactness is of considerable importance.

I claim as my invention—

1. In a pneumatic motor, the combination with a shaft having a plurality of cranks, of a series of pneumatics connected with said

cranks, a wind-board having air-channels leading to the respective pneumatics, each of said channels being provided in one of its walls with a suction-port and an air-inlet port arranged in line with each other lengthwise of the channel, sliding suction and inlet valves applied to the corresponding ports of each of said air-channels, a connection between the suction and air-inlet valves of each pair, and means for connecting each pair of valves with the companion crank on said shaft, substantially as set forth. 70 75

2. In a pneumatic motor, the combination with a shaft having a plurality of cranks, of a series of pneumatics connected with said cranks, an upright wind-board having vertical air-channels leading to the respective pneumatics, each of said channels being provided in one of its walls with a suction-port and an air-inlet port arranged one above the other, 80 85 sliding suction and air-inlet valves applied to the corresponding ports of each air-channel, a connection between the suction and air-inlet valves of each pair which causes one of said valves to be opened when the other is closed, and means for connecting each pair of valves with the companion crank on said shaft, substantially as set forth. 90

3. In a pneumatic motor, the combination with a shaft having a plurality of cranks, of a series of pneumatics connected with said cranks, a wind-board having upright air-channels leading to the respective pneumatics, each of said channels being provided in one of its walls with a suction-port and an air-inlet port arranged above the suction-port, a suction-chamber applied to said wall over each of said suction-ports and arranged below the corresponding air-inlet port, sliding suction-valves arranged in said chambers and controlling the corresponding ports, sliding valves applied to said air-inlet ports, a connection between the suction and air-inlet valves of each pair, and means for connecting each pair of valves with the companion crank on said shaft, substantially as set forth. 95 100 105

4. In a pneumatic motor, the combination with a shaft having a plurality of cranks, of a series of pneumatics connected with said cranks, a wind-board having air-channels leading to said pneumatics, each of said channels being provided with an air-inlet port, air-inlet valves applied to said ports, a suction-channel, valve-chambers connected by separate ports with said air-channels and said suction-channel, the ports leading from said valve-chambers to said air-channels being open at all times, suction-valves arranged in said valve-chambers and applied to the ports leading from said suction-channel to said chambers, 110 115 120 125 and means for transmitting the motion of said cranks to said air-inlet and suction valves, substantially as set forth.

5. In a pneumatic motor, the combination with a shaft having a plurality of cranks, of 130

a series of pneumatics connected with said cranks, a wind-board having air-channels leading to the respective pneumatics, each of said channels having an air-inlet port, valves applied to said ports, a suction-channel arranged below said air-channels and separated therefrom by an intervening partition, suction-chambers arranged below said air-inlet ports and each connected with said suction-chamber 5 and one of said air-channels by separate ports located on opposite sides of said partition, suction-valves applied to the ports which connect said suction-chambers with said suction-channel, and means for transmitting the motion of said cranks to said suction and air-inlet valves, substantially as set forth.

6. In a pneumatic motor, the combination with a shaft having a plurality of cranks, of a series of pneumatics connected with said 10 cranks, a wind-board having air-channels leading to said pneumatics, each of said channels

being provided with an air-inlet port and a suction-port arranged one above the other, sliding air-inlet and suction valves applied to the corresponding ports of each of said channels, one valve of each pair being provided with a pin and the other with a lug having a screw-threaded opening, a connecting-rod for each pair of valves provided at one end with an opening for receiving said pin and at the other end with a screw-thread engaging in said lug, and a rod connecting each pair of valves with one of said cranks and composed of sections having their inner ends adjustably connected by a longitudinal screw, substantially as set forth. 25

Witness my hand this 12th day of November, 1903.

EUGENE DE KLEIST.
